UNITED STATES PATENT OFFICE

ARTHUR C. AVRIL, OF CINCINNATI, OHIO

CONTAINER FOR TRANSPORTING AND MIXING CONCRETE

Application filed December 15, 1928. Serial No. 326,303.

My invention relates to containers or drums such as are used on vehicles for transporting mixed concrete, and particularly to the type of vehicle shown in my co-pending application Ser. No. 319,630, filed November 15, 1928. It relates specifically to an improved drum structure which facilitates the rapid filling and emptying of a non-tilting drum.

In the type of containers now in use, considerable equipment is required to insure proper delivery of the material inside of the container through the opening thereof. The most common type of drum is one mounted with tilting equipment for end delivery. It is not always easy to insure complete flow of the concrete therefrom; but in any event the tilting equipment is costly and cumbersome. In my co-pending application above referred to, I have described and claimed a type of transporting equipment, in which the drum does not tilt, but is held horizontally, and filled and emptied through a closable port. In this type also it is sometimes difficult to insure complete emptying; and frequently the material has had to be assisted through the port. Any mixing baffles inside the container have always hindered rather than facilitated the emptying of it.

It is an object of my invention to provide a horizontal and non-tilting drum which may be completely emptied very quickly and easily.

It is another object of my invention to provide means within the drum for guiding the material to the port, which means will also facilitate the mixing of the concrete during transportation.

Another object is to provide a drum with an improved outlet or port, which is easily operable, and is not resisted in opening by the material within the drum.

These and other objects of my invention which will be more specifically pointed out in the ensuing disclosure, or will be obvious therefrom to one skilled in the art, I accomplish by that certain construction and arrangement of parts of which I shall now describe a preferred embodiment, reference being had to the drawings which accompany these specifications.

In the drawings:

Figure 1 is a side elevation of my drum.

Figure 2 is a front elevation of my drum.

Figure 3 is a section of the drum taken on the line 3—3 of Figure 2. 55

Figure 4 is a section taken along the line 4—4 of Figure 2.

Figure 5 is a section taken on the line 5—5 of Figure 3.

Figure 6 is a section through the port and 60 valve taken on the line 6—6 of Figure 2.

Figure 7 is a perspective of the valve gate removed from the drum.

Figure 8 is a section through the clearout 65 opening of my drum.

I have shown a cylindrical drum 1 with tapered ends 2 terminating in a flat surface 3 upon which is fastened a flanged bearing 4 for mounting the container on a shaft 5. This shaft is mounted and free to rotate in bearings provided on vehicles such as shown in my copending application above referred to. It will be understood that mixed concrete is transported upon such vehicles in the drum, and that the drum is kept revolving during 70 such transportation. 75

Within the drum I locate plates 6 fastened to the drum as by welding, and slanting from the tapered ends of the drum toward a port, presently to be described, located in the side 80 of the drum between the ends. Another plate 7 is also disposed at an angle within the drum,

and slants from the port toward a position on the side of the drum, and between the first plates. Tight joints are made at all meeting 85 lines between the plates, and the plates and the drum. When the drum is disposed as shown in Figure 3, these plates form a hopper to conduct material toward the port. All

three plates terminate on another plate 8 90 which forms the bottom of a built-in chute, and the side plates 9 and plate 8 form the rectangular discharge opening for my container. This opening is on a line tangent with the outside of the cylinder forming my drum. 95

On the outside of my discharge opening I have fixedly mounted valve gate guides 10 with grooves 11 in which tongues 12 on the valve-gate 12^a are free to slide. On each side of the valve-gate I have fixedly mounted 100

a rack 13^a for sliding the valve-gate in its retaining grooves. Meshing with the racks are two spur gears 13 fixedly mounted on a shaft 14 which is rotatively mounted in bearings 15. These bearings are fixed to the valve-gate guides which are also rigidly mounted on the container. The ends of the shaft 14 have been squared so as to receive a socket wrench 16 which is the means provided for turning the shaft and gears thereon and thereby opening or closing the valve.

At the top of my drum I have provided an opening 17 with a closing cap 18 to permit of cleaning or loading my drum, or flushing it with water.

When my drum is mounted on a vehicle it can be rotated or held stationary as desired. It is my intention to rotate the drum especially while transporting the material, thereby keeping it properly mixed and soft. It will be seen that the guide plates within my container will also act as baffles and agitate the material so that there will be constant intermixing of the ingredients. When I wish to unload my drum, I turn it into the position shown in Figure 3, and open the valve gate the desired amount. The material readily flows from within the drum because it is flowing over sloping guides forming a hopper and directing it to the port.

Having thus described my invention, what I claim as new and desire to secure by Letters Patent, is:—

1. In combination with a vehicle for transporting mixed materials, a rotatable non-tilting drum with an outlet port, said port having a bottom wall extending tangentially to the walls of said drum, and baffling means within said drum disposed to direct the flow of material toward said port.

2. A device for handling mixed materials, a rotatable drum having an outlet port with a removable closure, said port having a bottom wall extending tangentially to the walls of said drum, said drum constructed and arranged to form a hopper to direct material toward said port.

3. A device for handling mixed materials, a rotatable drum having an outlet port with a removable closure, and members within said drum forming a hopper to direct material toward said port, said closure located approximately tangentially to said drum, and said hopper terminating in a chute, the sides of which form said port.

4. A device for handling mixed materials, a rotatable drum having an outlet port with a removable closure, and members within said drum forming a hopper to direct material toward said port, said closure located approximately tangentially to said drum, and said hopper terminating in a chute, the sides of which form said port, said chute and said closure forming part of the wall of said drum.

5. In a device for handling mixed concrete,

a horizontally pivoted, non-tilting drum, plates disposed within said drum to form a hopper, members defining an outlet port disposed substantially tangentially to said drum, a plate disposed substantially tangentially to said drum and substantially at right angles to said port forming a chute, the portion of said drum between said port and said plate cut away, said hopper disposed to conduct material through said opening, suitable plates closing the sides of said chute, and a removable closure for said port.
